HANDLE FOR AN ULTRASONIC BOND TESTING PROBE OR SIMILAR ARTICLE

Charles S. Phelan, Tustin, Calif., assignor to Shurtronics
Corporation, a corporation of California

Filed Nov. 13, 1968, Ser. No. 14,429

Term of patent 14 years

Int. Cl. D9—04

U.S. Cl. D52—1

FIG. 1.

FIG. 2.

FIG. 3.

FIG. 4.

FIG. 5.

FIG. 1 is a perspective view of a handle for an ultrasonic bond testing probe or similar article viewed from the top and one side thereof, showing my new design;

FIG. 2 is an elevational view of the side opposite to the side seen in FIG. 1;

FIG. 3 is a front elevational view;

FIG. 4 is a rear elevational view; and

FIG. 5 is a bottom plan view.

The broken line portions of the drawings are shown for illustrative purposes only.

What is claimed is:

The ornamental design for a handle for an ultrasonic bond testing probe or similar article, as shown and described.
